UNITED STATES PATENT OFFICE

WILLIAM HUSSEY ADAMS, OF KENYON, RHODE ISLAND, ASSIGNOR TO EASTERN FINISHING WORKS, OF KENYON, RHODE ISLAND, A CORPORATION OF RHODE ISLAND

DESIGN FOR A PRINTED TEXTILE FABRIC

Application filed March 21, 1929. Serial No. 30,581. Term of patent 7 years.

To all whom it may concern:

Be it known that I, WILLIAM H. ADAMS, a citizen of the United States, residing at Kenyon, in the county of Washington and State of Rhode Island, have invented a new, original, and ornamental Design for Printed Textile Fabric, of which the following is a specification, reference being had to the accompanying drawing, forming part thereof.

In the drawings, which illustrate a length

of fabric embodying my new design, the shading is to represent different colors but no particular colors.

I claim:

The ornamental design for a printed textile fabric, as shown and described.

In testimony whereof I have signed my name to this specification.

WILLIAM HUSSEY ADAMS.
